CLAIM

The ornamental design for a quadruple cup carrier as shown and described.

DESCRIPTION

FIG. 1 is an isometric view of a quadruple cup carrier of my new design;

FIG. 2 is a right side elevation view thereof, the left side elevation view is a mirrored image of FIG. 2;

FIG. 3 is a top plan view thereof;

FIG. 4 is a bottom plan view thereof; and,

FIG. 5 is a front elevation view thereof.

The broken lines in the form of four cups depict environmental subject matter and form no part of the claimed design.

1 Claim, 3 Drawing Sheets
